UNITED STATES PATENT OFFICE.

JAMES A. GRANT, THOMAS M. McCLELLAND, AND JAMES T. DRUMMOND,
OF MOUNT PLEASANT, IOWA.

DITCHING-MACHINE.

SPECIFICATION forming part of Letters Patent No. 259,304, dated June 13, 1882.

Application filed September 22, 1880. (No model.)

To all whom it may concern:

Be it known that we, JAMES A. GRANT, THOMAS M. McCLELLAND, and JAMES T. DRUMMOND, all citizens of the United States, 5 residing at Mount Pleasant, in the county of Henry and State of Iowa, have invented a new and useful Improvement in Ditching-Machines, of which the following is a specification.

Our invention relates to an improvement in 10 that class of ditching-machines designed more particularly for making tile-drains, being so constructed as to plow, elevate the dirt, and deposit it at the sides of the ditch by successively repeating its operation until the proper 15 depth of ditch is attained, and has for its object a more effective and improved method and mechanism for cutting or plowing a ditch and finishing it, so as to have its bottom level or properly graded for drainage, and also for elevating and depositing the dirt at the sides of 20 the ditch, than have hitherto been known.

Our invention consists, first, in a plow with 25 its cutting-edge of a depressed V shape, being also dilated at that point, and having a rearward termination in an upward curved trough, slightly diverging from a true circle, and provided also with one or more detachable segments or sections to be attached in lengthening 30 said trough, as the depth of ditch is increased, for the purpose of conducting the dirt from the plow to the surface beside the ditch.

It consists, second, in an elevating-wheel, a little less in diameter than the inner radial dimensions of said trough, which is loosely pivoted to the adjustable frame-work of the plow, 35 and is provided with a series of scrapers and check-braces, all pivoted to its periphery for the purpose of revolving said wheel by means of coming in contact with the ground forward 40 of and in the plow during the forward movement of the machine. Said scrapers also, as the wheel is revolved, elevate the dirt from the plow by scraping it up the curved trough in rear, from whence it falls in a lateral-issuing 45 guide-chute, and is deposited at the side of the ditch.

It consists, third, in a leveling device made to attach in rear of the plow or elevating-trough, so as to travel in the bottom of the ditch, which 50 has a spirit-level arranged on standards hav-

ing graduating-scales attached thereto, so as to indicate the degree or angle of pitch in finishing the bottom of ditches.

It consists, fourth, in mechanism herein shown for simultaneously raising or lowering 55 all of said parts to suit the varied requirements in making ditches.

In order to more fully set forth the mechanism of our invention by which said objects are attained, we submit the accompanying illustrative drawings, in which—

Figure 1 is a side elevation of the machine; Fig. 2, a plan view, looking from above; Fig. 3, an end elevation viewed from the rear, and Fig. 4 an end elevation viewed from the front. 65 The other figures are all perspective of detached parts, of which Fig. 5 represents the leveling device of the machine; Fig. 6, the upright frame or guide-standards supporting and through the internal grooves of which the main 70 plow-frame slides in its vertical adjustments. Fig. 7 is the center stirrup of the adjustable frame carrying the plow, and is also the support of the elevator-wheel, which is pivoted in it, and also of the elevator-trough, which is attached to it by means of braces and bolts or otherwise, so that when its height is regulated 75 all of said parts move together. Fig. 8 is the plow, forming also part of the elevating-trough. Fig. 9 is a detachable section of the elevator-trough. Fig. 10 is a segment of the elevating-wheel. Fig. 11 is one of the scrapers, and Fig. 12 a check-brace. One of each of the latter two figures is pivoted to each set of the lugs on the periphery of the wheel, Fig. 10. Fig. 85 13 is an upright frame or vertical trackway, rigidly fastened to the forward part of the side pieces of the main frame of the machine, for the purpose of guiding and forming a bearing for the traveler, shown at Fig. 14, which 90 traveler, being suspended by a rope playing over a pulley at the top of the frame, Fig. 13, plays vertically in the rabbets formed in the front edges of the side pieces of said frame. It constitutes an adjustable device, to which is 95 attached the forward draft of the plow. Fig. 15 is a bifurcated draft-bar connecting with the extensions at the forward part of the plow, Fig. 8, and with the shaft of the traveler, Fig. 14, thus obtaining an adjustable draft for the 100

plow from the forward part of the machine. Fig. 16 is a pair of rolling cutters to be placed in the bearings formed in the projections extending from the forks of the draft-bar, Fig. 15.

5 In the drawings, in which similar letters of reference indicate like parts in all, dotted lines representing parts hid from view, A is the main supporting frame-work of the machine, which rests on and is carried by wheels 10 arranged on axles in the usual way.

A' is an upright frame, rigidly fastened and braced to the side frame-pieces, A, the further use and description of which have been given in describing Fig. 6.

15 A'' is also an upright frame, fastened and braced to the frame A near its forward end, which has also been further described in the illustration, Fig. 13.

20 B is the main supporting-stirrup or center adjustable frame-work of the plow and elevating mechanism. It is suspended by a rope passing over one of the pulleys X at the top of the frame A'. Said rope extends back and connects with the windlass L. The lower end 25 of said stirrup extends around underneath and is rigidly fastened to the plow C, and to it are also fastened braces S, supporting said plow both fore and aft, as well as also the elevating-trough consisting of C and C'. (See further 30 the description of Fig. 7.)

C is the plow, constituting also part of the curved elevating-trough for conducting the plowed dirt out of the ditch. It is formed in shape transversely, having a depressed center approximating a letter V, which shape serves a double purpose: first, for cutting the dirt in an angular shape, so that it will easily yield in passing the contraction of the sides of the plow in rear of its cutting-edge; and, 40 secondly, for finishing a ditch with a center depression adapted for the convenient reception of tile. Said plow is dilated at its forward part or cutting-edge for the purpose of enlarging the ditch, so as to admit freely of the passage 45 of the necessary frame-work. Its rear portion and upper edges are also curved upward, forming an arc a little larger and slightly diverging from the periphery of the wheel D, thus forming part of the conducting-trough 50 for elevating dirt.

C' is a detachable section of the elevating-trough, being made to fit, and is fastened by bolting or otherwise, to the upper and rear end of the plow and trough-piece C, being thus 55 constructed with sectional partings in said trough in order to obviate the necessity of raising the discharged dirt to an unnecessary height while making a shallow ditch. Said detachable sections may be multiplied as circumstances 60 may require.

D is the elevating-wheel, which is pivoted in the stirrup or frame B, and is provided with projecting lugs i, arranged in pairs on its periphery, to which are loosely pivoted the scrapers e, Fig. 11, and the check-braces f, Fig. 12. The hinge part of said scrapers work outside 65 of said lugs and the check-braces between

them. Said scrapers and braces, when free from contact with the dirt, adjust themselves by their own gravity. The braces f, being 70 curved with a short bend near their pivot end as a suitable shape, are attached so as to fold respectively in rear of the scrapers as relates to the revolving motion of said wheel. The scrapers e in approaching the plow in their 75 downward movement so gravitate as to cause their arms successively to take in between the upper edges of the plow and the periphery of the wheel, thus assuming a position pointing outward and a little forward of a line radiating from the center of said wheel D, so that their points will strike the ground in proper position, and will, as said wheel revolves in its forward movement, press them directly point forward into the ground, and by being 80 thus held while passing over the plow and edges of the trough C and C', they elevate the plowed dirt by scraping it upward in said trough to where it is discharged, when by their own gravity they fall backward, discharging the dirt. The check-braces f also fall over with their points striking the ground forward of said wheel, when, by means of both the check-brace and scraper, whose arms are limited in their rearward movement, coming in 85 contact with the ground, and by a forward movement of the machine, the wheel is rolled forward and the scraper pressed into the ground, and thereby the plowed dirt is elevated through the curved trough for deposit 90 beside of the ditch; also, as the machine is advanced the check-braces are made to yield by pressure of the dirt, so as to fold within the recesses made for them in the rim of the wheel. 105

Z is a concave chute, hung to the frame-work in a diagonal position crosswise of the machine, in rear of and under the discharging end of the elevating-trough, for the purpose of catching the dirt as it falls and for conducting it to the sides of the ditch. 110

E is a traveler having friction-rollers b for traveling in the rabbets of the frame A'', Fig. 13, as the machine is raised or lowered, and by its connection with the plow by means of the bar I it becomes an adjustable draft for said plow. 115

F is the leveling device, partly described in describing Fig. 5. It is provided with a hinge joint at its forward end for coupling to a projection, c, on the rear of the plow C or C', as the case may be. It is also provided with a wheel, F', for traveling in the ditch, and with lateral projections or their equivalents on its sides for guiding said wheel F' at all times to 120 the center of said ditch. It is steadied in its upright position by means of rods or bars v, projecting from the frame A backward past its sides. It is also provided with a spirit-level arranged on its horizontal beam, being fixed 125 to two upward-projecting arms from said beam, each of said arms having a graduating-scale for fixing said level to any desired degree of inclination or declination from a true level for 130
